UNITED STATES PATENT OFFICE.

ISAAC E. PALMER, OF MIDDLETOWN, CONNECTICUT, ASSIGNOR TO THE I. E. PALMER COMPANY, OF MIDDLETOWN, CONNECTICUT, A CORPORATION OF CONNECTICUT.

COUCH-HAMMOCK.

No. 901,936.

Specification of Letters Patent.

Patented Oct. 20, 1908.

Application filed March 28, 1908. Serial No. 423,914.

To all whom it may concern:

Be it known that I, ISAAC E. PALMER, a citizen of the United States, residing at Middletown, in the county of Middlesex, State of Connecticut, have invented an Improvement in Couch-Hammocks, of which the following description, in connection with the accompanying drawings, is a specification, like letters on the drawings representing like parts.

This invention relates to hammocks of the type disclosed in my Patent No. 574,073, Dec. 29, 1896.

In order that the principles of the invention may be clearly understood, I have disclosed certain types or embodiments thereof in the accompanying drawings, wherein

Figure 1 is a perspective view of one end of a hammock embodying my invention; Fig. 2 is an end elevation, partially in section, of such form of hammock; Fig. 3 is a perspective view of a modified form of hammock; Fig. 4 is a longitudinal vertical section of a frame embodying my invention having the hammock cloth applied thereto; Fig. 5 is a plan view, upon an enlarged scale, of a corner of the frame represented in section in Fig. 4; Fig. 6 is a side elevation thereof; Fig. 7 is a view similar to Fig. 5, but representing a modified construction; Fig. 8 is a side elevation of the construction represented in Fig. 7; Fig. 9 is a side elevation of a form of casting that may be employed in the practice of my invention; Fig. 10 is a perspective view of the form of casting represented in Fig. 9 viewed from the inner side; Fig. 11 is a perspective view of a portion of one end of the frame and hammock cloth attached thereto; Fig. 12 is a view in vertical longitudinal section of a portion of a hammock frame and body and of a corner bracket having provisions for maintaining the body of the hammock laterally distended; Fig. 13 is a detail in plan of that portion of the hammock body wherewith the bracket engages to maintain the same laterally distended; Fig. 14 is an edge view of the construction shown in Fig. 13; Fig. 15 is a plan view of the form of bracket preferably used in the practice of my invention; Fig. 16 is a side elevation thereof; and Fig. 17 is a detail in section representing the means shown in Fig. 11 for

securing the lateral edges of the hammock body.

Hammocks have heretofore been constructed with frames interrupting the natural curvature of the body thereof, such as shown for example in my Patent No. 574,073, Dec. 29, 1896. Therein the frame is provided with a plurality of cross rungs as at the front and rear. The body of the hammock is passed under such cross rungs and above the intermediate portion of the frame, so as to rest thereon. As disclosed in said patent, the frame may be of angular form or may be flat. While it is apparent that the frame disclosed in the said patent and in my present application may be of any suitable length, it is herein represented as of sufficient length to receive the entire person of the user, so as to support the same in a substantially horizontal position.

Referring more particularly to Figs. 4 and 5 of the drawing, the frame therein represented is composed of longitudinal or side members 1-1 and transverse or end members 2-2 suitably connected thereto in any desired manner, as by bolts or screws 3 indicated in Figs. 5 and 7. Any other suitable fastening means may be employed. If desired, each member of the frame may be recessed to receive the other, as indicated in dotted lines in Figs. 6 and 8. Upon each corner portion of the frame, and as represented in detail in Figs. 5 and 6, is received a bracket or casting 4 adapted to be secured thereto in any suitable manner, as, for example, by screws 5-5 received in a suitable opening or openings in the upper surface of the casting and the screw 6 received in a suitable opening in the lower face of the casting. It is apparent that the said brackets may be attached to either the end or longitudinal members of the frame, or both if desired. Herein, I have represented the bracket as provided with upper and lower flanges which may be of the form indicated at 7 and 8 respectively in Fig. 10 or of any other desired shape. In Figs. 5 and 7, the upper flange is represented as provided with an opening 9, within portions of which the screws 5-5 are received. Similarly and as indicated in dotted lines in Fig. 5, the lower flange may be provided with an opening, 105 within which a holding screw 6 may be re-

ceived. As indicated in Figs. 5, 6 and 10, the bracket 4 is provided at the outer end thereof with a socket 10, herein represented as inverted and preferably somewhat inclined to support the rod or bar in that position. As herein represented, the socket extends from the face of the longitudinal member or body of the bracket or casting. This permits that portion of the hammock 10 cloth that passes beneath the cross rods supported by the brackets to be of the full width of the body of the cloth or of the frame. While such socket may be of any desired peripheral extent and may completely encircle the rod or bar if desired, it is preferably interrupted to permit the insertion of the said rod or bar from below. Within the opposite brackets 4, and preferably at each end of the frame, are received rods, bars or 20 bearings 11 of any suitable shape. If desired, the sockets 10 may be provided with openings to receive screws 12 which, passing into the rod or bar 11, positively holds the same in place. It will be apparent that in 25 the form of the invention herein shown, the relation and construction of the sockets are such that each rod or bearing is held from endwise movement.

In Fig. 7, I have represented the socket 10 as provided with an opening 13, within which is received the head of a screw 14 projecting from the rod or bar 11, the said screw head preferably overlapping the edge of the casting, thereby aiding in securing the same in position. The extent of the opening 13 is such as to permit, if desired, a slight rocking movement of the rod or bar 11 in the socket. In Figs. 4, 5 and 6, the rods or bars 11 are represented as elongated in cross section. The said bars may be of substantially the same size throughout.

The body of the hammock may be formed of any suitable material. Preferably, however, it is made of fabric, as indicated at 16 in Fig. 3, each end of the body being, as indicated in said figure, provided with a spreader 17, from which extend any suitable fastening means, as cords 18, by which the hammock may be suspended from any suitable support. The fabric 16 of the hammock may be continuous from end to end, as represented in Fig. 4. In said figure, the fabric is represented as passing beneath the rods or bars 11 at opposite ends of the frame, upon the upper surface whereof said fabric rests intermediate said rods or bars. This construction, and more particularly with the form of bracket shown in Figs. 15 and 16, permits the inverting of the frame 60 and of the hammock cloth, so that the frame is supported upon the cloth. In Fig. 4, I have represented the fabric as reinforced beneath the rods or bars 11 as indicated at 19. If desired, and preferably I provide

at opposite ends of the hammock transverse 65 webs 20 suitably secured at opposite edges to the main fabric of the hammock, as indicated at 21—21, the rods or bars 11 being thus received within pockets 22, which may be of any desired size. A pillow may be 70 placed within either pocket 22, represented in Fig. 4, or the pillow may be placed against the outer surface of either strip or web 20. If it be not desired to place a pillow within either pocket 22, access may be 75 had to the pocket for any purpose, as to permit the placing of a book or the like therein in any suitable manner. In Fig. 1, I have represented the web 20 as stitched along its upper edge to the body 16 for a 80 portion of its length, as represented at 23 and 24, the intermediate portion of the edge being unattached for the purpose stated. If desired, and as represented in dotted lines in said Fig. 1, the ends of the pocket may 85 be left open. If desired, a pocket may be provided at either or both ends to receive the rods or bars 11, and in addition thereto and overlying the same pockets of any suitable description may be provided, as, for example, the pockets 25 and 26, indicated in Fig. 3, the said pockets being open at their upper edges to permit the insertion of any desired articles.

In Fig. 11, I have represented at 23* the 95 web 20 as stitched to the fabric 16 from edge to edge of the latter. Preferably, to the edges of the fabric 16 are attached the valances, one of which is indicated at 27 in Fig. 3. The end portion of each valance may, as 100 indicated in Fig. 1, be attached to the end of the webs 20, so as to overhang and conceal the ends of the pockets 22. The valances may be continued around to the back of the upright portion of the hammock at 105 either or both ends to any desired extent for purposes of ornamentation or for convenience of construction.

Inasmuch as there is some liability of wear of the fabric 16 or its reinforce where 110 it passes beneath the rods or bars 11, I may provide any suitable means to bind the fabric at such point against the frame. In Figs. 7 and 8, I have represented a rod or bar 11 as provided with a lateral wing 28, 115 preferably extending from one socket 10 to the opposite socket and adapted, as indicated in dotted lines in Fig. 8, to bear upon the web 16, where the same is received upon the outer edge of the end member 2 of the 120 frame, as indicated at 29. Since the cross bar is permitted, in the construction shown in Figs. 7 and 8, a slight rocking movement in the sockets, it will be apparent that when the hammock is in use the tension upon the 125 fabric 16 in the direction of the arrow represented in Fig. 8 tends to rock the rod or bar 11 in the direction of the arrow adja-

cent thereto in said figure. Thus, the wing 28 impinges upon the fabric 16 at the point 29 and binds the same against the end member 2 and prevents a rubbing or wearing 5 action of the fabric.

If desired, I may employ suitable means for securing the hammock fabric to the frame. While this may be done in any desired manner, I have, in Figs. 11 and 17, represented straps 30 secured to the under face of the fabric 16 and adapted to underlie the longitudinal members 1 and to be removably secured thereto in any suitable manner, as by the provision of an eye in each strap to be received over suitable hooks 31 indicated in dotted lines in Fig. 11 and full lines in Fig. 17. If desired, both faces of the longitudinal members 1 may be provided with suitable securing means, thus 20 permitting the fastening of the straps, whichever side of the frame be uppermost.

It will be apparent that the hammock frame may be detached from the fabric 16 by removing the rods or bars 11 from the 25 sockets 10 and the pockets 22. This may be desired for convenience in shipment or for storage, or it may be desired to invert the frame. Viewing Fig. 5, it will be apparent that if it be desired to invert the 30 frame when using the form of bracket there shown, the brackets 4 may be removed therefrom and each bracket be secured to the opposite corner at the same end upon the opposite face of the frame. It will moreover 35 be apparent that the brackets may be readily detached from the frame for any purpose by removing the screw 5-5 and 6 represented in Figs. 5 and 6. Referring to the form of casting represented in Fig. 10, it 40 will be apparent that the screw openings represented in the webs or flanges 7 and 8 may be omitted and that one or more screws or bolts may be passed through a suitable opening in the body of the casting. In 45 Figs. 9 and 10, the casting is represented as provided with an elongated opening or openings 32 to lighten the casting. If desired, such opening or openings may be of reduced extent, and a circular opening of proper 50 diameter may be provided to receive a single bolt. In this manner, each bracket may be secured to the edge of the longitudinal member 1 or 2.

If desired, the corner castings at one or 55 both ends may be consolidated, so as to form a single casting at either end extending the width of the frame and provided with suitable sockets for supporting the cross rod or bar.

60 In Figs. 12, 15 and 16, I have indicated a form of corner casting preferably employed and which permits reversal of the frame for use without detachment of said brackets. In said figures, the longitudinal portion 66

of the bracket is provided with laterally extending webs, the upper one of which is shown at 67, to be received upon the upper and lower faces of the frame. The bracket may be attached to the frame permanently in any suitable manner, as by bolts 68 passing 65 through the upper and lower webs. The longitudinal portion 66, instead of being inclined upwardly in the manner illustrated in Figs. 9 and 10, extends substantially straight, as represented most clearly in Fig. 70 16, and is provided at a suitable point near its end with a socket 69 to receive the cross bar 70. The cross bar may be mounted for removal in any suitable manner. Herein, I have represented the same as provided with 75 a groove or socket upon its upper face, wherein is secured a spring like member 71, the end 72 whereof normally extend above the surface of the cross bar to engage the inner lateral face of the castings 69, thereby 80 preventing longitudinal movement of the cross bar in the castings. By depressing the end 72 of the spring like member 71, the cross bar may be withdrawn from the brackets. Preferably, each end of the cross bar is 85 provided with means, such as herein referred to, for maintaining it in position.

I contemplate the provision of means to maintain the body of the hammock laterally distended. I have, in Figs. 11 and 17, represented straps 30 secured to the body of the hammock and adapted to be engaged with the frame. I may, in conjunction with such means or without the use thereof, provide the corner brackets with suitable means to 90 maintain the body laterally distended. In 95 Fig. 13, I have represented the corner bracket as provided with upper and lower segmental flanges 73, 74 of suitable extent adapted to engage trough like formations 100 in the contacting portion of the body 16. While said trough like formations may be provided in any suitable manner, I preferably form an opening as 75 in that portion 105 of the body that contacts with the bracket and sew along the edges thereof a strip of webbing 76 gathered at the ends, as indicated at 77 in Fig. 14, to provide terminal 110 portions. Either flange 73 or 74 may be received in the trough like formations 75, 115 it being apparent that the lateral walls 78 and 79 thereof will grip the sides of the flange tightly, thus maintaining the edges 120 of the body fabric at the edges of the frame. It is apparent that instead of forming an 125 opening in the fabric, the webs 76 may be attached to the lateral edges of the body fabric, being gathered in the manner described to form troughs for the reception of the flanges. The length of the trough like formations should preferably be greater than the length of the flange received therein, thus permitting longitudinal move-

ment of the fabric of the hammock relative to the bracket. It will be apparent that the illustration in Figs. 13 and 14 is to a considerable extent diagrammatic and is exaggerated to make more clear the operation. In practice, the opening 75 may be merely a slit.

Having thus described one type or embodiment of my invention, I desire it to be understood that although specific terms are employed, they are used in a generic and descriptive sense and not for purposes of limitation, the scope of the invention being set forth in the following claims.

Claims.

15. 1. A hammock frame adapted for engagement with a hammock and provided at its ends with cross rods and with means independent of the hammock for spacing said cross rods from said ends and for supporting them against displacement at both faces of said frame to permit reversal of the frame.
20. 2. A reversible hammock frame provided with end members, cross rods, and means independent of the hammock for spacing said cross rods from said end members to leave suspension spaces and for supporting said cross rods against displacement at both faces of said frame to permit reversal of the frame.
25. 3. A hammock frame provided at its ends with hammock engaging members combined with a hammock having portions extended above and below said engaging members and in supporting engagement therewith, whereby is produced a reversible framed hammock, the portion whereof between the ends of said frame is maintained under hammock supporting tension.
30. 4. A hammock frame having connected transversely disposed end suspension members, combined with a hammock overlying said frame and provided with portions passing above and below said suspension members and supporting means for said suspension members permitting frame reversal.
35. 5. A hammock frame adapted for engagement with a hammock and provided at its ends with brackets and cross rods spaced from said ends, said brackets encircling said cross rods sufficiently to support said frame with either face uppermost.
40. 6. A hammock frame adapted for engagement with a hammock and provided at its ends with brackets having one or more portions disposed in substantial parallelism with a face of the frame and secured thereto and having rod supporting portions extending longitudinally beyond the end members of the frame and cross rods spaced from said frame and supported by said brackets against displacement at both faces of said frame.
45. 7. A hammock body provided at one or both ends with a transverse pocket, a frame

independent of said body and provided with a bearing to be received within said pocket, and corner brackets attached to the main portion of said frame and supporting said bearing spaced from said main portion.

8. A hammock body having transverse pockets at opposite end portions thereof, a frame independent of said body, provided with bearings adapted to be received within said pockets, and corner brackets connecting said bearings to the main portion of the frame.

9. A hammock body having a transverse web secured thereto at one or both ends upon the upper face thereof to provide a pocket or pockets, a frame independent of the body of the hammock and provided with a bearing or bearings for insertion in said pocket or pockets, and corner brackets connecting said bearing or bearings to the main portion of said frame.

10. A hammock frame independent of the body of the hammock, but adapted to engage therewith to interrupt the natural curvature thereof, said frame being provided with corner brackets, each of which has a longitudinal portion engaging a lateral edge of the frame and extending longitudinally beyond the frame, each bracket being provided with a socket spaced from the frame and adapted to receive a cross rod, the socket being so disposed that the cross rods may be supported in the plane of the frame, thereby permitting reversal of the frame for use without detaching the brackets.

11. A hammock comprising a main fabric body having a transverse web attached thereto at an end portion along transverse lines the said web being separated for a portion of its length from the main body portion along one of said transverse lines to provide a pocket.

12. A fabric hammock body, a frame independent of said body and having a bearing or bearings adapted to overlie portions of said fabric body and a reinforcing member or members applied to the hammock body where said bearing or bearings overlie the same.

13. A hammock body, a hammock frame independent of the body but adapted to engage therewith and provided with end members, cross rods supported by said frame and spaced from said end members for the passage of supporting portions of the hammock body, the said body having one or more lateral strips extending therefrom, and means detachably to secure the same to the under surface of said frame.

14. A hammock body, a frame independent of the body, and provided with bearings to engage the hammock body, one or more of said bearings being adapted to overlie a portion of the body and provided with

- means to bind the body from rubbing or wearing movement.
15. A hammock body, a frame independent of the body, and provided with bearings to engage the hammock body, one or more of said bearings being adapted to overlie a portion of the body and provided with means to bind the body against the main portion of the frame.
- 10 16. A hammock body, a frame independent thereof and provided with bearings adapted to engage the body, said frame having longitudinal and transverse end members, and a plurality of bearings spaced from 15 said end members, one or both of said bearings being provided with a lateral wing adapted to overlie a portion of the body and to bind the same against the adjacent end member.
- 20 17. A hammock frame independent of the body of a hammock but adapted to engage therewith, said frame having connected end members and provided at each end with corner brackets and cross rods supported by 25 said brackets and spaced from said end members for the passage between the rods and the end members of portions of the hammock body, the said corner brackets holding the said rods against longitudinal 30 movement in the line of the axes of said rods.
18. A hammock attachment comprising a frame independent of the body of the hammock and provided with bearings for the body of the hammock, the said bearings 35 being so located with respect to one another that the hammock body may be engaged therewith one or more of said bearings being held from longitudinal movement, but mounted for rocking movement.
- 40 19. A hammock attachment comprising a frame independent of the body of the hammock and provided with bearings for the body of the hammock, the said bearings being so located with respect to one another 45 that the hammock body may be engaged therewith one or more of said bearings being held from longitudinal movement, but mounted for rocking movement, said bearing or bearings being provided with means 50 to bind the body of the hammock against said frame.
20. A hammock frame independent of the body of the hammock but adapted to engage therewith and provided with connected 55 end members, cross rods supported by the frame and spaced from said end members for the passage therebetween of portions of the hammock body, the lateral edges of said hammock body having means detachably 60 connecting the same to the frame but permitting the ready detachment thereof.
21. A hammock frame independent of the body of the hammock but adapted to engage therewith, said frame having connected end 65 members and provided at each end with
- brackets and cross rods supported by said brackets and spaced from said end members for the passage therebetween of supporting portions of the hammock body, the said brackets having provisions to maintain the 70 body of the hammock laterally distended.
22. A hammock comprising a body, a frame provided with bearings to engage the body of the hammock, corner brackets supporting said bearings, and means attached 75 to said hammock to cover one or both of said bearings.
23. A hammock comprising a body, a frame having bearings at its opposite ends, corner brackets supporting said bearings, 80 and webs attached to the body of the hammock and overlying said bearings.
24. A hammock frame adapted for engagement with a hammock and provided at its ends with brackets having one or more 85 portions disposed in substantial parallelism with a face of the frame and secured thereto and having portions extending longitudinally beyond the end members of the frame, bearings extending inwardly from said longitudinally extending portions, and cross rods supported by said bearings and spaced 90 thereby from the end members of the frame.
25. A hammock body, a frame independent thereof and adapted to be applied thereto, corner brackets secured to said frame, cross bars supported in said corner brackets and spaced from the body of the frame, one or more of said brackets being provided 95 with a flange or flanges to engage the body 100 fabric to maintain the same laterally distended.
26. A hammock frame independent of the body of the hammock but adapted to engage therewith, said frame having longitudinal 105 and end members and transverse bearings or cross rods supported by the ends of said frame and spaced from the end members thereof, the hammock body being adapted to lie upon the upper surface of said frame and having portions passing both above and beneath said rods or bearings.
27. A frame adapted to be applied to a hammock and comprising connected end members, brackets secured to and extending 110 longitudinally beyond said frame in substantially the plane thereof and having cross rod supporting bearings and cross rods spaced from said end members and held 115 from displacement by said bearings with either face of said frame uppermost.
28. A rectangular hammock frame comprising longitudinally disposed members and transversely disposed end suspension members, combined with a hammock overlying said frame and provided with portions passing above and below said suspension members whereby said frame may be reversed.
29. A hammock frame having connected 120

transversely disposed end suspension members, combined with a hammock overlying said frame and provided with portions passing above and below said suspension members, and means preventing lateral displacement of the hammock body and hammock frame with respect to each other.

In testimony whereof, I have signed my name to this specification, in the presence of two subscribing witnesses.

ISAAC E. PALMER.
